Specification of Letters Patent.

Patented Dec. 14, 1915.

Application filed June 15, 1914. Serial No. 845,207.

To all whom it may concern:

Be it known that we, JOHN H. BARR and EDWIN E. BARNEY, citizens of the United States, and residents, respectively, of the 5 borough of Manhattan, city of New York, in the county of New York and State of New York, and Ilion, in the county of Herkimer and State of New York, have invented certain new and useful Improvements 10 in Type-Writing Machines, of which the following is a specification.

This invention relates to improvements in the typebar-systems of front-stroke type-writing machines, and in escapement actuating mechanism thereof, which includes, and the operation of which depends on, the whole typebar-system, the object of the invention, generally stated, being to better the construction and operation of the typeactions 20 and mechanism actuated by them, especially in single shift-machines in which the segment instead of the platen shifts. The invention consists of mechanism embodied in a front-stroke typewriting machine, and including the features of construction, combinations, and arrangement of parts herein-after described and specified in the claims.

In the accompanying drawings, in which like reference numerals designate like parts 30 in different views, and which illustrate portions of a front-stroke typewriting machine containing the invention,

Figure 1 is a central, vertical, longitudinal section, and side elevation, of the frame and some of the mechanism of the machine; Fig. 2, a vertical cross section, on the plane indicated by the line *x*, *x*, Fig. 1, of the frame and some of the mechanism, a front elevation of parts both in front of and behind that plane, and a diagrammatic illustration of some parts; Fig. 3, a vertical cross section and rear elevation of portions of the frame and mechanism, the section being on planes indicated by the lines *y*, *y*, Fig. 1; 45 and Fig. 4, an enlarged perspective of a device called a pusher.

The frame of the machine is composed of five castings, 1, 2, 3, 4 and 5, the last being the top-plate. Each of the castings 1 and 2 forms a side of the base and includes two of the posts 6 by which the top-plate is supported and to which it is affixed. The sides of the base and the castings 3 and 4, which are respectively the front and rear

portions of the base, are fastened together with tap-bolts, four of these, 7, being shown in Fig. 1. The fixed plate 8, in the rear part 4 of the base, forms the fulcrum of the typekey-levers 9 and the two levers 10 of the space-bar 11. The levers 10 have downwardly extending ears 10' and are connected together by a cross-rod 12 affixed to these ears, and are provided with restoring-springs 12'. All of these levers extend through slots in the comb 13 fixed in the part 3 of the base. The typekey-levers 9 are connected by links 14 with a set of angular levers, mounted on a fixed support above the key-levers, each lever 9 having on it a hook 15 and each link being forked at its lower end and engaged with a hook, which passes through the fork and over a pivot-pin fast at its ends in the branches of the fork. A flat spring 16, riveted to the lever and extending close to the back of the link, normally keeps the latter engaged with the hook but allows it easily to be disengaged therefrom. These angular levers, 17, are punched from thin, flat stock and are all alike, each having a rearwardly extending arm 18 and an upwardly extending arm 19, and the links 14 are connected to the arms 18. The support 20 of the levers 17 is made from sheet-metal, and has the form shown by Figs. 1 and 2. The levers 17 are pivoted on horizontal axes in hangers 21 which project from the back of the support 20 and have flat stems 22 which extend through holes in the support and are upset on its front face (Fig. 2). The support is attached by screws 23 to lugs 24 formed on the top plate, and is connected by the bar 25 with the part 3 of the frame.

The typebar-segment 26 and typebar-rest 27 are firmly fastened together by means of the two side-rods 28 and the central bar 29, and are supported on the two arms 30, near the sides, and the links, or double link 31, about midway between the sides, of the machine. The arms 30 are fast on the shaft 32, supported by the lugs 33, formed on the top plate, and are pivoted at their front ends to the lugs 34 (Fig. 3) formed on the segment, the shaft 32 being a rock-shaft. The links 31 (Figs. 1 and 3) are mounted at their rear ends on the pin 35, supported by the bracket 36, affixed to the part 4 of the frame, and are pivotally connected at their front

ends by the pin 37 to the arms 38 of a bracket having the top 39 through which extends the stud 40 that is fast in the lug 41, formed on and projecting from the back 5 of the segment. This stud also passes through the bail-shaped bar 42, and this bar and the top 39 of the bracket just described are clamped together and firmly but adjustably attached to the stud by nuts 43 which 10 engage with screw-threads on the stud. A spacing-sleeve which fits closely between the links 31 is shown surrounding the pin 37. The arms 30 are parallel and equal in length and their pivotal axes are parallel to and 15 equally distant from the plane which contains the pivotal axes of the links 31, the length of which may equal, or be somewhat less or greater than, that of the arms 30. Between the links 31 is a frame formed from 20 a piece of sheet-metal and having the back 44, and the sides 45 which are connected together by the pin 46 on which is the roller 47. This frame is attached to the links 31 by the bolts or screws 48 and 49 which extend through the links, and through the slots 50 and 51 in the sides of the frame, and on which are spacing-sleeves 52, closely fitting between the sides 45. The roller may 25 be raised and lowered by loosening the bolt 48 and turning the frame on the bolt 49, and may be moved forward and backward by loosening the bolt 49 and turning the frame on the other bolt, and therefore is properly adjustable with relation to the cam 53 having 30 the slot 54 through which the roller extends. This cam is fast on the shaft 55, which is a rock-shaft, connected at its ends to the sides of the frame, and on which, near its ends, are the arms 56, connected by 35 the links 57 with the shiftkey-levers 58, fastened to the shaft 59, which is also a rock-shaft, connected at its ends to the sides of the frame. The bar 42 is attached near the sides of the machine to the vertical rods 60, 40 which are fast at their upper ends in the lugs 61 on the back of the segment and pass through the bar, which is adjustably fastened on the rods by nuts 62, and the parts 63 of this bar extend under the blocks 64, 45 cast on the sides of the frame, and on each of these parts are pads 65. The coil-spring 66, attached at its upper end to the screw 67, extending through and below the top-plate, and at its lower end to the spacing-sleeve 55 on the bolt 48, normally keeps the links 31, arms 30, segment, typebar-rest and bar 42, in the positions in which they are shown, and then the pads 65 on the upper sides of the parts 63 of the bar 42 are 60 in contact with the blocks 64. The blocks 68, which are cast on the machine-frame directly under the blocks 64, and the screws 69 and 70 which project from the tops of these blocks, support the plates 71 and enable 65 them to be adjusted with relation to

the parts 63 of the bar 42. The screws 69 pass through these plates and the screws 70 are normally tightly set against the under sides of the plates. When lower-case writing is done the segment and type-rest are in 70 the positions in which they are shown, and when they are shifted to enable upper-case characters to be written, the operation of a shift-key rocks the cam 53, and the front ends of the links 31 are pulled down until 75 the downward movement of the bar 42, and of the segment and type-rest is arrested by the stop-plates 71. By this operation the coil-spring 66 is stretched, and when the shift-key is released this spring raises the 80 segment and type-rest to their normal positions, their upward movement being arrested by the stop-blocks 64 and bar 42.

The type-bars are pivoted to hangers attached to the front face of the segment 26, 85 on which they are arranged in two curved rows, one containing the hangers 72 and the other the hangers 73 of the type-bars 74 and 75 respectively, which normally lie near their front ends on the pad 76 that forms 90 part of the typebar-rest.

In construction and arrangement the type-bars and hangers do not differ materially from those of well known Remington machines. That part of the typebar-rest which 95 is behind the pad 76 is much like a slotted typebar-segment in form, and in the slots 77 thereof levers 78 are mounted on a common curved pivot-wire 79, the upper or inner arms of these levers extending close to the 100 convex side of the typebar-system and being connected with the type-bars by links 80, and the lower or outer arms of the levers 78 being connected by links 81 with the arms 19 of the angular levers 17 above described. 105 The median plane of each lever 78 is at right angles to the pivotal axis of the type-bar to which the lever is connected, and preferably coincides with the median plane of that type-bar, so that the median planes of the 110 levers of this set diverge as they recede from the convex side of the typebar-system, and the elevations of these levers increase in order from the middle to the ends of the set. The coil-springs 82, connected to the lower 115 or outer arms of the levers 78, and to the hooks 83, formed on the plate 84, attached to the front of the typebar-rest, are tension-springs which normally compel the levers to push on the links 80 and pull on the links 81, 120 so that the type-bars cannot rebound even slightly unless they overcome the resistance of these springs, and when a type-key is actuated there is no lost motion at any of the joints between the key-lever and the lever 78 125 on which the key-lever acts. The springs 82 will restore the typekey-levers, type-bars and the other parts of the type-actions to their normal positions, during the operation of the machine. When a type-bar is operated 130

the upper or inner end of the lever 78 then actuated moves into the space normally occupied by the type-bar, the construction described enabling the lever 78 so to act without interference from any of the other type-bars, and the force that operates the type-bar is confined to a single plane from the front end of the link 81 to the pivot of the type-bar. The lines *a* in Fig. 2 indicate grammatically the pivotal axes of several type-bars, and the lines *b* (Fig. 2) indicate planes which are the median planes of these type-bars and of the levers 78 connected thereto, and in which the forces act that are transmitted from those levers to the type-bars through the connecting links. The links 81 are so arranged that when the segment is in its shifted position they are inclined to the vertical plane containing the pivots of the levers 17 substantially to the same extent, but in a different direction, as they are when the segment is in its normal position, and this arrangement of the links 81, and the action on them of the springs 82 and levers 78 as above described, prevent or help to prevent, the shifting operation from producing a vibration such as is called a "wink" in either the type-bar-system or the key-board, for the swing of these links on their rear pivots, and the slight movement of the levers 78 on the front pivots of the links, there being lost-motion to be taken up in these joints, will not disturb the levers 17 or affect the relations of the levers 78 to the typebar-rest, links 80, type-bars and segment.

On the back of the segment is a curved and slotted rib, similar to that on the type-bar-rest, and in the slots 85 of this rib, and on a common pivot wire 86, is mounted the set of levers 87. The number of these levers equals that of the type-bars, and the median planes of the levers coincide with those of the type-bars, the elevations of the levers increasing in order from the middle to the ends of the set, and to these levers at their lower ends are connected the coil-springs 88, which are also connected to the hooks 89 and tend to force the upper or inner ends of the levers forward, these hooks being formed on the plate 99, which is fast on the segment.

The levers 87 extend through the guide-slots 91 in the curved plate 92, which fits on the concave edge of the segment and is fastened to it.

The curved guide-plate 93, containing the holes 94, arranged in two curved rows, is affixed to the plate 92, and through the holes 94 extend the pushers 95, each of which projects into the path of a type-bar and is engaged at its rear end with one of the levers 87.

The stock which forms the rear portion 96 of each pusher (Fig. 4) is fastened, and on the back of the fold is an oblong hole 97

through which the engaging lever 87 loosely passes, the pusher being confined between small projections formed on the lever.

At the front end of the folded portion 96 is the shoulder 98 which normally rests 70 against the plate 93, the front portion 99 of the pusher extending through the plate and being upturned at its front end 100. The pushers which project into the paths of the type-bars 74 pass through those holes 94 of 75 the guide-plate 93 which are in the inner row, and the pushers which project into the paths of the type-bars 75 pass through the holes 94 of the outer row.

When a type-bar is actuated it strikes the 86 front end 100 of the pusher on which it acts, just before the type reaches the platen 101, forcing backward the pusher and upper end of the lever engaged with it, and stretching the coil spring that is connected to the lever, 85 and instantly thereafter the type-bar is repelled by the joint action upon it of the spring, lever and pusher. It will be seen, therefore, that each pusher and the lever and spring connected therewith constitute a repelling device, and that the repelling devices equal the type-bars in number.

The rear edges 87 of the levers 87 are curved and act as rockers on the universal bar 102, with which they normally make contact about midway between the arc-shaped edges of the bar. The three arms 103, 104 and 105, affixed to this bar, are pivoted respectively at their rear ends to the upper ends of the upright arms 106, 107 and 108, the support of the arms 106 and 107 being the rock-shaft 109, and the support of the arm 108 being the rock-shaft 110, and these upright arms being fast on the rock-shafts. The axes of these rock-shafts are 105 in a vertical plane and each shaft is mounted at its ends in brackets 111 and 112, affixed to the top-plate of the machine. The arms 113 and 114, fast on the shaft 109 and, preferably, integral respectively with the arms 106 and 107, are connected by the links 115 and 116 with the arms 117 and 118, fast on the shaft 110. The tension springs 119 connected to the arms 117 and 118 and to the lugs 120 formed on the arms 106 and 107, tend to 115 keep the universal bar 102, the rock-shafts 109 and 110, and the arms and links which these rock-shafts support, in their normal positions.

The upright projection 121 of the arm 105, 120 is connected by the rod 122 with the dog-rocker 123 of the escapement of the machine, the rod passing into a hole in the dog-rocker above its shaft 124, and on this rod is the adjusting nut 125 which is close to the front of the rocker. The escapement-wheel 126, on which the dogs of the dog-rocker act, is mounted on a bracket 127 affixed to the top-plate and is connected by the clutch 128 with the pinion 129, which the carriage-rack 129

mally engages, the clutch and pinion being also mounted on the bracket 127. The arm 130, fast on the shaft 110, is connected by the rod or link 131 with the cross-rod 12, 5 through which the rod 131 loosely passes, and on the rod 131 under the cross-rod 12 are the nuts 132, the upper nut being normally in contact with the cross-rod, or nearly so.

The operation of the levers 87, through the 10 action of the type-bars on the pushers 95, as described, causes these levers so to rock on the universal bar 102 that this bar is pushed backward at each stroke of a type-key by the actuated lever 87, the bar swinging on the upright arms 106, 107 and 108, and slightly turning the rock shafts 109 and 110, and as the bar 102 moves backward the dog-rocker 123 is rocked by the action on it of the rod 122 and nut 125. The springs 119 15 and the dogrocker-spring (not shown) restore the universal bar, rod 122, and dog-rocker to their normal positions. The levers 87 rock on the universal bar 102 from about midway between its curved edges to or 20 nearly to its upper or inner edge, when the segment is in its normal position, but when the segment is shifted to its lower position the levers 87 descend so that in the operation of the machine in writing uppercase 25 characters these levers act on the universal bar from near its lower or outer edge to about midway between its curved edges. The depression of the space-key rocks the shafts 109 and 110 so that the universal bar 30 102 and rod 122 move backward and the dog-rocker is rocked as above described.

In consequence of the practice of the Patent Office concerning the division of applications, parts of the mechanism above described, which are believed to be novel and patentable, are not claimed herein, but the right to claim those parts in another application is not waived.

It will be understood that the invention 45 claimed below may be embodied in mechanism differing more or less in details of construction and arrangement of parts from that in which it is illustrated herein. We are not aware that a shifting set of type-bars arranged in two curved rows, and mechanism comprising a universal bar and a connection between it and the escapement, have heretofore been combined, so that, both when the typebar-support or segment is in its normal position and when it is in its shifted position, the universal bar will be properly actuated by the type-bars, and by the force of blows struck by them, and by portions thereof that are remote from the type-blocks, 50 55 where they travel much less rapidly than do portions near the type-blocks.

The shape and location of the universal bar, and the means through which the action of this bar is made to depend on blows struck 60 by the type-bars, are the result of numerous

inventive acts and experiments by which the mechanism described herein was developed, and that mechanism illustrates the invention in its preferred form.

What we claim as new and desire to secure by Letters Patent, is:—

1. In a front-stroke typewriting machine having a shifting segment and typebar-rest rigidly secured together, the combination of a system of type-bars mounted on the segment in two curved rows, links pivoted to the type-bars and extending from the back toward the front of the typebar-system, a set of levers mounted on the typebar-rest and connected with said links, pushers which equal the type-bars in number and are mounted on the segment in two curved rows and extend normally into the paths of the type-bars, and means, including a universal bar, for connecting the pushers with the escapement.

2. In a front-stroke typewriting machine having a shifting segment and typebar-rest rigidly secured together, the combination of a system of type-bars mounted on the segment, links pivoted to the type-bars and extending from the back toward the front of the typebar-system, a set of levers mounted on the typebar-rest and connected with said links, pushers which equal the type-bars in number and are mounted on the segment and extend normally into the paths of the type-bars, and means, including a universal bar, for connecting the pushers with the escapement.

3. In a front-stroke typewriting machine having a shifting segment and typebar-rest rigidly secured together, the combination of a system of type-bars mounted on the segment in two curved rows, links pivoted to the type-bars and extending from the back toward the front of the typebar-system, a set of levers mounted on the typebar-rest and connected with said links, and repulsing devices comprising pushers which equal the type-bars in number and are mounted on the segment in two curved rows and form parts of the escapement-actuating mechanism.

4. In a front-stroke typewriting machine having a shifting segment and typebar-rest rigidly secured together, the combination of a system of type-bars mounted on the segment, links pivoted to the type-bars and extending from the back toward the front of the typebar-system, a set of levers mounted on the typebar-rest and connected with said links, and repulsing devices which equal the type-bars in number and are mounted on the segment and form parts of the escapement-actuating mechanism.

5. In a front-stroke typewriting machine having a shifting segment and type-bars mounted thereon in two curved rows, the combination with the type-bars, of pushers which equal the type-bars in number and are

5 mounted on the segment in two curved rows and extend normally into the paths of the type-bars, and means, including a universal bar, for connecting the pushers with the escapement.

6. In a front-stroke typewriting machine having a shifting segment and type-bars mounted thereon in two curved rows, the combination with the type-bars, of pushers 10 which equal the type-bars in number and are mounted on the segment in two curved rows and extend normally into the paths of the type-bars, a like number of levers which are mounted on the segment and to which the 15 pushers are connected, a universal bar on which the levers act, and a connection between the universal bar and the escapement.

7. In a front-stroke typewriting machine having its type-bars arranged in two curved 20 rows, the combination with the type-bars, of pushers which equal the type-bars in number and are arranged in two curved rows and extend normally into the paths of the type-bars, and means, including a universal 25 bar, for connecting the pushers with the escapement.

8. In a front-stroke typewriting machine having its type-bars arranged in two curved rows, the combination with the type-bars, of 30 pushers which equal the type-bars in number and are arranged in two curved rows and extend normally into the paths of the type-bars, a like number of levers to which the 35 pushers are connected, a universal bar on which the levers act, and a connection between the universal bar and the escapement.

9. In a front-stroke typewriting machine having a shifting segment and type-bars mounted thereon in two curved rows, the 40 combination with the type-bars, of repulsing devices comprising pushers which equal the type-bars in number and are mounted on the segment in two curved rows and form parts of the escapement-actuating mechanism.

10. In a front-stroke typewriting machine having its type-bars arranged in two curved rows, the combination with the type-bars, of repulsing devices comprising pushers 50 which equal the type-bars in number and are arranged in two curved rows and form parts of the escapement-actuating mechanism.

11. In a front-stroke typewriting machine having a shifting segment, the combination 55 with the type-bars, of pushers which equal the type-bars in number and are mounted on the segment and extend normally into the paths of the type-bars, a like number of levers which are mounted on the segment and 60 to which the pushers are connected, springs that tend to keep the levers in their normal positions, a universal bar on which the levers act, and a connection between the universal bar and the escapement.

65 12. In a front-stroke typewriting machine

having a shifting segment, the combination with the type-bars, of pushers which equal the type-bars in number and are mounted on the segment and extend normally into the paths of the type-bars, a like number of levers which are mounted on a common curved pivot-wire secured to the segment at the back thereof, a universal bar on which the levers act, and a connection between the universal bar and the escapement, the pushers 70 being at different elevations and connected to said levers.

13. In a front-stroke typewriting machine having a shifting segment, the combination with the type-bars, of pushers which equal the type-bars in number and are mounted on the segment and extend normally into the paths of the type-bars, a like number of levers which are mounted on the segment and to which the pushers are connected and 80 which have curved edges, a universal bar on which said curved edges of the levers act, and a connection between the universal bar and the escapement.

14. In a front-stroke typewriting machine 90 having a shifting segment, the combination with the type-bars, of pushers which equal the type-bars in number and are mounted on the segment and extend normally into the paths of the type-bars, a like number of levers which are mounted on the segment at elevations which increase in order from the middle to the ends of the set of levers, a universal bar on which the levers act, and a connection between the universal bar and the 95 escapement, the pushers also being at different elevations and being connected to said levers.

15. In a front-stroke typewriting machine 100 having a shifting segment, the combination with the type-bars, of pushers which equal the type-bars in number and are mounted on the segment and extend normally into the paths of the type-bars, a like number of levers which are mounted on the segment and 105 to which the pushers are connected, a universal bar on which the levers act, and a connection between the universal bar and the escapement.

16. In a front-stroke typewriting machine, 115 the combination with the type-bars, of pushers which equal the type-bars in number and extend normally into the paths of the latter, a like number of levers to which the pushers are connected, springs that tend to keep the levers in their normal positions, a universal bar on which the levers act, and a connection between the universal bar and the escapement.

17. In a front-stroke typewriting machine, 125 the combination with the type-bars, of pushers which equal the type-bars in number and extend normally into the paths of the latter, a like number of levers to which the pushers are connected, the levers being at 130

- elevations which increase in order from the middle to the ends of the set of levers and the median plane of each lever being at right angles to the pivotal axis of a type-bar, a universal bar on which the levers act, and a connection between the universal bar and the escapement.
18. In a front-stroke typewriting machine, the combination with the type-bars, of pushers which equal the type-bars in number and extend normally into the paths of the latter, a like number of levers to which the pushers are connected and which have curved edges, a universal bar on which said curved edges of the levers act, and a connection between the universal bar and the escapement.
19. In a front-stroke typewriting machine, the combination with the type-bars, of pushers which equal the type-bars in number and extend normally into the paths of the latter, a like number of levers to which the pushers are connected, the levers being at elevations which increase in order from the middle to the ends of the set of levers, a universal bar on which the levers act, and a connection between the universal bar and the escapement.
20. In a front-stroke typewriting machine, the combination with the type-bars, of pushers which equal the type-bars in number and extend normally into the paths of the latter, a like number of levers to which the pushers are connected, a universal bar on which the levers act, and a connection between the universal bar and the escapement.
21. In a front-stroke typewriting machine having a shifting segment, the combination with the type-bars, of repulsing devices which equal the type-bars in number and each of which comprises a pusher and a lever that form parts of the escapement-actuating mechanism, the levers being mounted on a common curved pivot-wire secured to the segment at the back thereof, and the pushers being mounted on the segment and extending forward and backward therefrom and being connected at their rear ends with the levers.
22. In a front-stroke typewriting machine having a shifting segment, the combination with the type-bars, of repulsing devices which equal the type-bars in number and are mounted on the segment and form parts of the escapement-actuating mechanism and each of which comprises a pusher and a lever, the levers being on a common curved pivot-wire at the back of the segment.
23. In a front-stroke typewriting machine having a shifting segment, the combination with the type-bars, of repulsing devices which equal the type-bars in number and are mounted on the segment and form parts of the escapement-actuating mechanism and each of which comprises a pusher and a lever, the levers being at the back of
- the segment and the median plane of each being at right angles to the pivotal axis of a type-bar.
24. In a front-stroke typewriting machine having a shifting segment, the combination with the type-bars, of repulsing devices which equal the type-bars in number and are mounted on the segment, and form parts of the escapement-actuating mechanism, and each of which comprises a pusher and a lever.
25. In a front-stroke typewriting machine, the combination of a shifting set of type-bars, and escapement-actuating mechanism including a shifting set of repulsing devices which equal the type-bars in number, each repulsing device comprising a pusher which normally extends into the path of a type-bar between its pivotal axis and the printing point.
26. In a front-stroke typewriting machine, the combination with the type-bars, of repulsing devices which equal the type-bars in number and each of which comprises a pusher and a lever which form parts of the escapement-actuating mechanism, the levers being mounted on a common curved pivot-wire at the back of the type-bar system.
27. In a front-stroke typewriting machine, the combination with the type-bars, of repulsing devices which equal the type-bars in number and each of which comprises a pusher, a lever and a spring which form parts of the escapement-actuating mechanism, the spring tending to keep the lever in its normal position.
28. In a front-stroke typewriting machine, the combination with the type-bars, of repulsing devices which equal the type-bars in number and each of which comprises a pusher and a lever which form parts of the escapement-actuating mechanism and co-act with but one type-bar, the median plane of the lever being at right angles to the pivotal axis of the type-bar.
29. In a front-stroke typewriting machine, the combination with the type-bars, of repulsing devices which equal the type-bars in number and each of which comprises a pusher and a lever which form parts of the escapement-actuating mechanism.
30. In a front-stroke typewriting machine, the combination with the type-bars, of repulsing devices which equal the type-bars in number and include the same number of springs all constantly under tension, and form parts of the escapement-actuating mechanism, each repulsing device comprising a pusher which normally extends into the path of a type-bar between its pivotal axis and the printing point.
31. In a front-stroke typewriting machine, the combination with a system of pivoted type-bars, and links pivoted to the type-bars and extending from the back to-

ward the front of the typebar-system, of a set of levers having upper arms that are connected to the front ends of said links, and having also lower arms, another set of links connected to said lower arms and extending backward therefrom, a set of angular levers connected to the rear ends of the links of the latter set, a set of links connected to said angular levers and extending downward therefrom, a set of key levers to which the last mentioned links are connected, and springs connected to the lower arms of the levers of the first mentioned set and tending to draw the lower ends of these arms forward.

32. In a front-stroke typewriting machine, the combination with a shifting segment and typebar rest rigidly secured together, a system of type-bars mounted on the segment, and links pivoted to the type bars and extending from the back toward the front of the typebar-system, of a set of levers mounted on the typebar-rest and on a common curved pivot-wire, the levers being connected with said links, and the median plane of each lever being also that of the type-bar to which the lever is connected.

33. In a front-stroke typewriting machine, the combination with a shifting segment and typebar-rest rigidly secured together, a system of type-bars mounted on the segment, and links pivoted to the type-bars and extending from the back toward the front of the typebar-system, of a set of levers mounted on the type bar-rest at different elevations and connected with said links, the elevations of the levers increasing in order from the middle to the ends of the set, and the medium plane of each lever being also that of the type-bar to which the lever is connected.

34. In a front-stroke typewriting machine, the combination with a shifting segment and typebar-rest rigidly secured together, a system of type-bars mounted on the segment, and links pivoted to the type-bars and extending from the back toward the front of the typebar-system, of a set of levers mounted on the typebar-rest and connected with said links, the median plane of each lever being also that of the type-bar to which the lever is connected.

35. In a front-stroke typewriting machine, the combination with a shifting segment and typebar-rest rigidly secured together, a system of type-bars mounted on the segment, and links pivoted to the type-bars and extending from the back toward the front of the typebar-system, of a set of levers mounted on the typebar-rest and on a common curved pivot-wire, the levers being connected with said links.

36. In a front-stroke typewriting machine, the combination with a shifting segment and typebar-rest rigidly secured to-

gether, a system or type-bars mounted on the segment, and links pivoted to the type-bars and extending from the back toward the front of the typebar-system, of a set of levers mounted on the typebar-rest at different elevations and connected with said links, the elevations of the levers increasing in order from the middle to the ends of the set, and the median planes of the levers diverging as they recede from the convex side of the typebar-system.

37. In a front-stroke typewriting machine, the combination with a shifting segment and typebar-rest rigidly secured together, a system of type-bars mounted on the segment, and links pivoted to the type-bars and extending from the back toward the front of the typebar-system, of a set of levers which are mounted on the typebar-rest and connected with said links, and the median planes of which diverge as they recede from the convex side of the typebar-system.

38. In a front-stroke typewriting machine, the combination with a system of pivoted type-bars, and links pivoted to the type-bars and extending from the back toward the front of the typebar-system, of a set of levers extending backward and upward from their support and connected at their upper ends with the front ends of said links, the elevations of the levers increasing in order from the middle to the ends of the set, the median plane of each lever being at right angles to the pivotal axis of the typebar to which the lever is connected, and the upper ends of the levers being near the typebar-system and being movable into the spaces normally occupied by the type-bars.

39. In a front-stroke typewriting machine, the combination with a system of pivoted type-bars, and links pivoted to the type-bars and extending from the back toward the front of the typebar-system, of a set of levers connected with said links at their front ends, the elevations of the levers increasing in order from the middle to the ends of the set, and the median plane of each lever being at right angles to the pivotal axis of the type-bar to which the lever is connected, a series of links pivoted to said levers and extending backward therefrom, and a set of key-actuated levers to which the last mentioned links are pivoted at their rear ends.

40. In a front-stroke typewriting machine, the combination with a system of pivoted type-bars, and links pivoted to the type-bars and extending from the back toward the front of the typebar-system, of a set of levers connected with said links at their front ends, the median plane of each lever being at right angles to the pivotal axis of the type bar to which the lever is connected, a set of links pivoted to said

levers and extending backward therefrom, and a set of key-actuated levers to which the last mentioned links are pivoted at their rear ends.

- 5 41. In a front-stroke typewriting machine, the combination of a shifting set of type-bars, a non-shifting universal bar connected with the escapement, and means subject to impact by the type-bars and operative thereby to actuate the universal bar, both when the type-bars are operated from their normal positions and when they are operated from their shifted positions, said means being out of contact with the type bars except when they are in and near their printing positions, and comprising a set of separately movable devices which equal the type bars in number and each of which acts immediately on the universal bar.
- 10 42. In a front-stroke typewriting machine, the combination of a shifting set of type bars, a non-shifting universal bar connected with the escapement, and means subject to impact by the type-bars and operative thereby to actuate the universal bar, both when the type-bars are operated from their normal positions and when they are operated from their shifted positions, said means comprising a set of pushers which 15 equal the type bars in number and normally extend into the paths of the type bars.
- 15 43. In a front-stroke typewriting machine, the combination of a shifting set of type-bars, a non-shifting universal bar connected with the escapement, and means subject to impact by the type-bars and operative thereby to actuate the universal bar, both when the type-bars are operated from their normal positions and when they are operated from their shifted positions, said means comprising a set of pushers which 20

- 25 44. In a front-stroke typewriting machine, the combination of a shifting set of type-bars, a non-shifting universal bar connected with the escapement, and means subject to impact by the type-bars and operative thereby to actuate the universal bar, both when the type-bars are operated from their normal positions and when they are operated from their shifted positions, said means comprising a set of pushers which 25

normally extend into the paths of the type-bars, and a set of levers on which the pushers act and which act on the universal bar.

44. In a front-stroke typewriting machine, the combination of a shifting set of type-bars arranged in two curved rows, a non-shifting universal bar connected with the escapement, and means subject to impact by the type-bars and operated thereby to actuate the universal bar, both when the type-bars are operated from their normal positions and when they are operated from their shifted positions, said means comprising a set of pushers arranged in two curved rows and normally extending into the paths of the type-bars.

45. In a front-stroke typewriting machine, the combination of a shifting set of type-bars arranged in two curved rows, and mechanism comprising a universal bar, and a connection between it and the escapement, said mechanism being operative by the impact of the type-bars thereon both when they are operated from their normal positions and when they are operated from their shifted positions.

Signed at the borough of Manhattan, city of New York, in the county of New York, and State of New York, this 10th day of June A. D. 1914.
